(57) **CLAIM**

We claim the ornamental design for a three hole swivel clamp, as shown and described.

DESCRIPTION

FIG. 1 is a perspective view of a three hole swivel clamp depicting, in part, the new, original and ornamental design thereof.

FIG. 2 is a perspective view of the three hole swivel clamp showing the underside thereof.

FIG. 3 is a right side elevation view of the three hole swivel clamp of FIG. 1.

FIG. 4 is a left side elevation view of the three hole swivel clamp of FIG. 1.

FIG. 5 is a front elevation view of the three hole swivel clamp of FIG. 1.

FIG. 6 is a rear elevation view of the three hole swivel clamp of FIG. 1.

FIG. 7 is a top plan view of the three hole swivel clamp of FIG. 1; and,

FIG. 8 is a bottom plan view of the three hole swivel clamp of FIG. 1.

The broken lines in the drawing figures depict environmental structure or portions of the three hole swivel clamp for illustrative purposes only, and form no part of the claimed design.
